UNITED STATES PATENT OFFICE.

GEORGE L. KIER, OF PHILADELPHIA, AND DAVID R. RICHIE, OF LANSDOWNE, PENNSYLVANIA, ASSIGNORS TO S. L. ALLEN & CO., INC., A CORPORATION OF PENNSYLVANIA.

BACK REST FOR SLEDS.

Application filed February 28, 1927. Serial No. 171,405.

Among the principal objects of our invention are to provide a back rest which may be readily attached to or detached from a sled of ordinary construction; which is readily adjustable to different widths of sleds and which, when detached from the sled, may be compactly folded for shipment or storage.

Other objects of the invention are to provide a back rest having the foregoing characteristics and which comprises but a relatively small number of parts and these of a construction and design not liable to be damaged or get out of order under the usual conditions of operation to which devices of this character are customarily subjected, which, because of its simplicity, may be readily attached to and removed from the sled by a child or other inexperienced person and in which those portions so disposed as to be instinctively grasped by the person seated on the sled are preferably constructed of wood or other substantially similar material as distinguished from metal which latter is extremely cold to the touch under the conditions of temperature in which sleds are customarily used.

Still further objects of the invention are to provide a back rest of novel construction which may be manufactured at relatively low cost and thus sold at retail at a price sufficiently moderate to appeal to the prospective purchaser, as well as to provide a back rest embodying various novel features of design, construction and arrangement to which reference is hereinafter more particularly made.

To enable those skilled in the art to comprehend and practice the invention we have illustrated in the accompanying drawings and will now proceed to describe a preferred embodiment thereof, Fig. 1 being a perspective view of the back rest positioned on a sled of well known form and Fig. 2 a top plan view of the back rest and sled shown in Fig. 1. Fig. 3 is an enlarged detail view in end elevation of one of the clamps employed for securing the back rest uprights to the side rails of the sled and Fig. 4 is a perspective view of the clamp removed from the side rail and upright and with the clamping bolt omitted. Fig. 5 is a somewhat diagrammatic composite top plan view designed to illustrate the adjustability of the back rest to different widths of sleds and Fig. 6 is a top plan view of the back rest removed from the sled and

with the parts folded flat for shipment or storage.

The sled to which we have shown the back rest as attached in Figs. 1 and 2 is of well known construction, comprising runners R above which are supported cross members C through the medium of struts S secured to the runners and to the cross members which latter serve in turn to support longitudinally extending boards forming the top T of the sled as well as side rails R which are slightly spaced laterally from the top and, like the latter, are firmly secured to the cross members. While this particular type of sled is well suited for the attachment of our back rest it is to be understood that the latter if desired may be employed with equal facility upon substantially any other type of sled.

In its preferred embodiment and as shown, the back rest itself comprises, generally speaking, a pair of uprights 1, 1 whose lower ends are respectively adapted for attachment to the side rails of the sled conveniently by the clamps hereinafter more particularly described; a plurality, conveniently a pair, of substantially U-shaped back supports 2, 3 of somewhat flexible material such as relatively thin strips of steel having their free ends pivotally secured respectively to the uprights in spaced relation; means for maintaining the uprights in substantially vertical position, and means for holding the back supports 2 and 3 in substantially horizontal position when the back rest is operatively attached to the sled.

More specifically, the free or forward ends of the upper back support 2 may be respectively connected to the upper ends of the uprights 1 by pivots 4 and the corresponding ends of the back support 3 similarly respectively connected to the uprights by pivots 5 which are preferably disposed a little above the centers of the uprights thus, as the lower ends of the latter when the back rest is in position on the sled extend somewhat below the side rails R, the back support 3 will be positioned about midway between the surface of the top T and the upper ends of the uprights. As best shown in Figs. 2 and 6 the back support 2 is somewhat longer than the back support 3 so that as the forward ends of the supports are disposed in substantially the same vertical plane when on the sled the center of the support 2 will be somewhat fur-

ther to the rear than the corresponding point on the support 3 and the length of the arc described by the former somewhat greater than that described by the latter. This arrangement and disposition of the back supports is desirable in that it enhances the comfort of the person sitting on the sled for as the back supports form that portion of the device which is engaged by the back of such 10 person the latter is thus enabled to lean back a little instead of being compelled to sit directly upright as would be the case if the back supports were both of the same length.

For maintaining the back supports substantially parallel and in horizontal or approximately horizontal position, we provide a spacing member or brace 6, preferably formed of a relatively stiff and non-flexible piece of flat steel, and pivotally secure the 20 same to the center of the lower back support 3 by means of a rivet 7 in such manner that the lower end 7' of the brace will rest on the top T when the brace is in vertical and the back support 3 in substantially horizontal position. For removably securing the upper end of the brace to the upper back support 2 at the center of the latter, we preferably provide the support with a squared hole 8 adapted for the reception of a bolt 9 correspondingly squared adjacent its head; this bolt may be passed rearwardly through the hole 8 and a suitably positioned and preferably squared hole near the end of the brace and secured in position by a wing nut 10 on its 35 projecting end. Thus when the brace is turned to vertical position and secured to the back rest 2 by means of the bolt, both of the supports are firmly held in properly spaced relation with each other and also with the 40 top of the sled through engagement of the lower end of the brace therewith.

As the thrust exerted on the back rest by the person occupying the sled is principally exerted against the back supports 2 and 3 and would thus pull the uprights 1 toward the rear in the absence of means for resisting it, we respectively attach to the upper end of each of the uprights, preferably by means of the pivots 4, one end of a strut 12 whose 50 opposite end is pivotally secured by pivots 13 to the upper end of a short post 14 whose lower or opposite end is adapted to be secured to the side rails of the sled by a clamp of similar construction to that used for securing the corresponding ends of the uprights thereto. Preferably each of these posts is considerably shorter than the uprights 1 so that the struts when the back rest is in position on the sled incline forwardly 55 and downwardly from the uprights to the posts as clearly shown in Fig. 1, and as the lower ends of both the uprights and the posts are firmly secured to the rails of the sled, the struts are thus operative to prevent the uprights from being inclined either forward 60 or downwardly.

or back with the result that the whole back rest structure is securely tied together and adapted to afford adequate support to the occupant of the sled at all times.

As the struts are so disposed as to afford 70 natural hand grips for the person on the sled we prefer to make them of wood instead of metal as the former is far less cold to the touch and therefore does not chill the hands to so great an extent when grasped for an 75 period of time.

While any suitable means may be used for detachably securing the uprights and posts to the side rails R we prefer for that purpose to employ a peculiar form of clamp which is 80 best illustrated in Figs. 3 and 4. This clamp, generally designated as 20 and conveniently formed from a single piece of steel of suitable gage, comprises a rectangular body 21 having a squared hole 22 formed at its center and a 85 lug or flange 23 bent outward from its lower edge. The width of this flange measured at right angles to the body may be somewhat greater than the thickness of the side rails of the sled in connection with which the clamp 90 is to be employed and at its outer or free end is preferably provided with ears 24 spaced apart sufficiently to receive between them one of the posts 14 or uprights 1 which are 95 preferably all of the same width. It will be noted from Fig. 3 that the flange 23 is so directed with respect to the body 21 as to form an obtuse angle therewith which may desirably approximate 100° although the exact 100 relative angularity between the flange and the body is capable of some variation. The clamp may also be desirably provided with a pair of laterally spaced ears 25 adjacent the opposite or upper edge of the body; these 105 ears which extend from the same side of the body as the flange 23 may be inclined at an angle of approximately 45° to the body and are operative to bite into the wooden sled rail when the clamp is secured thereto. For 110 drawing the clamp into position against the rail and the upright or post, a bolt 26 having a squared portion adjacent its head adapted to cooperate with the squared hole 22 and a threaded portion at its other end adapted to receive a wing nut 27 may be employed, as 115 best shown in Fig. 3.

When utilizing the clamp to secure one of the uprights or posts to the sled rail R, the upright is first placed in vertical position against the outer face of the rail with the flat or widest side of the upright thereagainst. The clamp 20, conveniently with the bolt 26 pushed therethrough, is then moved toward the inner face of the rail in such manner that the free end of the bolt will pass through a hole 28 disposed near the lower end of the upright and the ears 25 be brought against the inner face of the rail with the ears 24 straddling the upright below the bolt. The wing nut is then placed on the projecting end 125 130

of the bolt and screwed firmly against the outer face of the upright, the latter being, if necessary, moved longitudinally along the rail or turned to approximately vertical position before the wing nut is finally set up. When thus secured in place the clamp, by reason of its peculiar conformation, is effective to hold the upright very securely to the rail, the ears 25 biting into the inner face of the latter and the flange 23 exerting, under the influence of the tightly drawn bolt, which is positioned substantially midway between the holding points of the clamp, a very powerful outward thrust against the lower end of the upright below the bolt which tends to force that portion of the upright which is above the bolt inwardly against the face of the rail with the result that the connection effected between the upright and the rail is so secure that outward pressure on the upper end of the upright is powerfully resisted and will ordinarily result in bending the upright at some point above the rail before effecting a visible separation between the upright and the rail at their point of contact. The use, therefore, of clamping means of the character described for effecting the necessary connection between the posts and uprights and the rails materially contributes to the ultimate rigidity of the whole of the back rest structure when operatively secured to the sled. Additionally, as the flanges 23 of the clamps are desirably made somewhat wider than the thickness of the average sled rail, the clamps may be used with rails of different sizes, while as the uprights and posts are preferably all of the same width, the several clamps may be interchanged; thereby making it unnecessary to select any particular clamp for use with any particular post or upright when attaching the back rest to the sled.

It is thought that the method of attaching the back rest to the sled will be readily apparent and that extended reference thereto would be superfluous. It may, however, be noted that owing to the flexibility of the back supports 2 and 3 it is possible to readily attach the back rest to sleds of different widths as indicated in Fig. 5. From an inspection of said figure it will be apparent that when it is desired to attach the back rest to a sled which is relatively narrow, the pivoted ends of the supports can be forced together from their normal position so as to bring the uprights and posts into proper relation with the side rails of the sled, thus, as shown in full lines, causing the supports to conform to a somewhat sharper curve and to extend further to the rear with respect to the uprights than would normally be the case. In like manner when attaching the back rest to a relatively wide sled the pivoted ends of the supports can be forced apart from their normal position, thus, as shown in dotted lines, flattening the curvature of the supports and bringing

their centers more nearly adjacent the uprights. In consequence, if in the manufacture of the back rest the supports are initially curved in such manner that their free ends and in turn the uprights are properly spaced apart for a sled of average width, the back rest may be readily attached to sleds of greater or less width than the average by springing the supports outwardly or inwardly in the manner just described, thus relieving the dealer from the necessity of carrying a large number of back rests of different sizes in order to meet the requirements of his customers and also permitting the owner of a single rest to selectively attach it to the different sized sleds which may be possessed by his children in accordance with their different ages.

It should be further noted that by reason of the pivotal connection between the back supports and the uprights, the like connection between the uprights and posts and the struts and between the brace 6 and the back support 2, the various parts, when the back rest is removed from the sled, may be folded about their several pivots so as to lie in a single plane as best shown in Fig. 6, the back rest under such conditions occupying a substantially rectangular space whose dimensions are substantially determined by the distance between and overall length of the struts and by the width of the back supports 2 and 3 or of the uprights, whichever may be the greater. In consequence, the back rest may be very readily packed for shipment in a flat and relatively shallow box occupying but little space and adapted to contain as well the clamps and bolts necessary for the attachment of the back rest to the sled and which are ordinarily removed when the back rest is sent out by the manufacturer. In like manner the back rest when detached from the sled may be folded up by the user and stored in a relatively small space or, if desired, left unfolded with the brace 6 in position and hung up in a closet or the like.

It will thus be apparent that we have provided a back rest for a sled which is of novel yet simple construction and affords numerous practical advantages not the least of which are its strength and rigidity when operatively positioned on the sled, its lightness and capability of being utilized on sleds of various widths and finally its ability when detached from the sled to be compactly folded for shipment or storage.

While we have herein described and illustrated a preferred form of our invention with considerable particularity we do not thereby desire or intend to specifically limit ourselves thereto as minor changes may be made in the design, construction and arrangement of the various parts when desired without departing from the spirit and scope of the invention as defined in the appended claims.

Having thus described our invention, we

claim and desire to protect by Letters Patent of the United States:

1. A detachable back rest for a sled comprising a pair of uprights respectively adapted for attachment to the side rails of the sled, a back support attached to each of said uprights, a brace relatively movable with respect to the back support and adapted when in one position to extend from the back support to the top of the sled, and a strut attached to each of said uprights, all of said parts being hingedly connected together and adapted to be folded into a single plane when detached from the sled.
2. A detachable back rest for a sled comprising a pair of uprights respectively adapted for attachment to the side rails of the sled, a substantially U-shaped back support of flexible material pivotally connected at its free ends to said uprights, a brace adapted to extend from the back support to the top of the sled, and a pair of rigid struts respectively pivotally connected to said uprights at one end, all of said parts being hingedly connected together to permit their being folded into a single plane when detached from the sled, and means carried by each of said struts adjacent its opposite end adapted for connection to a side rail of the sled.
3. A back rest for a sled comprising a pair of uprights respectively adapted for attachment to the side rails of the sled, a plurality of substantially U-shaped back supports of flexible material each pivotally connected at its ends to said uprights, a brace pivotally connected to the center of one of said supports and adapted to extend therefrom to the top of the sled and to another of the said supports, means for detachably connecting the brace to

said last mentioned support, a strut pivotally connected at one end to each of said uprights, and means disposed adjacent the opposite end of each strut adapted for attachment to a side rail of the sled.

4. A back rest for a sled comprising a pair of uprights respectively adapted for attachment to the slide rails of a sled, a plurality of back supports each pivoted to both of the uprights, a strut pivoted to each of the uprights, and means pivoted to each strut adapted for connection with the side rails of the sled, said means being adapted to be turned into parallelism with said struts and said struts and said back supports being each adapted to be turned into parallelism with the uprights whereby all the said parts when detached from the sled may be disposed in a single plane.

5. A back rest for a sled comprising a pair of uprights respectively adapted for attachment to the side rails of a sled, a plurality of flexible U-shaped back supports respectively pivoted to the uprights and adapted to be folded into parallelism therewith, a brace pivoted to the center of one of said supports and adapted to be folded into parallelism therewith or turned at right angles thereto to extend to another of the supports, a strut pivoted to each of said uprights and adapted to be folded into parallelism therewith, and means pivoted to each strut and capable of being turned into parallelism therewith adapted for connection to the side rails of the sled.

In witness whereof, we have hereunto set our hands this 25th day of February, 1927.

GEORGE L. KIER.
DAVID R. RICHIE.
